TO THE D. E. WHITON MACHINE COMPANY, OF NEW LONDON, CONNECTICUT, A
CORPORATION.

AUTOMATIC CONTROLLING APPARATUS FOR TANK-PUMPS.

1,384,287.

Specification of Letters Patent. Patented July 12, 1921.

Application filed March 13, 1920. Serial No. 365,654.

To all whom it may concern:

Be it known that we, LUCIUS E. WHITON and HENRY B. LEE, citizens of the United States, residing at New London, in the county of New London and State of Connecticut, have invented a new and useful Improvement in Automatic Controlling Apparatus for Tank-Pumps; and we do hereby declare the following, when taken 10 in connection with the accompanying drawings and the characters of reference marked thereon, to be a full, clear, and exact description of the same, and which said drawings constitute part of this application, and 15 represent, in—

Figure 1, a broken view in side elevation of a tank-pump installation embodying our improved automatic controlling apparatus, the tank, greatly reduced in size (proportionally), being shown in vertical section.

Fig. 2, a broken view partly in vertical central section and partly in elevation showing, the motor-controller, the hydraulic controller-operator, and the governor.

Fig. 3, a detached view in side elevation of the inner end of the hydraulic controller-operator.

Our invention relates to an improved automatic controlling apparatus for tank-pumps, the object being to effect an economy of motive power and to reduce the wear of the parts due to repeatedly stopping and starting the apparatus in response to slight falls in water-level which is the principle 30 on which apparatus of this character is now generally operated.

With these ends in view, our invention consists in an automatic controlling apparatus for tank-pumps, operated on the principle of a high and a low water-level, and having a tank, a tank-pump, a motor therefor, a motor-controller, and a hydraulic motor-controller operator including a siphon the high and low points of which substantially coincide with predetermined high and 40 low water-levels in the tank.

In carrying out our invention, as herein shown, we employ a hydraulic motor-controller operator having a siphon the short leg 2 of which is located within the tank 3 and extended downward thereinto to the low water-level thereof represented by the line 4 while its upper end is connected with a short horizontal pipe 5 lo-

cated at the high water-level 6 of the tank 55 in which it is mounted just below the edge thereof. The long leg 7 of the siphon, is located outside of the tank and connected at its upper end with the outer end of the pipe 5 and discharges at its lower end into 60 the water-pressure chamber 8 of a hydraulic motor-controller operator which is provided with a horizontally arranged, reciprocating operating-head 9 suspended, as it were, by and between vertically arranged dia- 65 phragms 10 and 11 of which the former forms the inner wall of the said water-pressure chamber 8, while the latter sus- pends the inner end of the said head 9 and forms the inner wall of a spring-chamber 70 12 containing a helical adjusting-spring 13 the tension of which is regulated by an adjusting-screw 14, the said spring and screw being co-axial with the head 9 and the two diaphragms. The said water- 75 pressure chamber 8 is provided at its lower end with an adjustable drip-cock 15 nor- mally left open.

The said operating-head 9 is formed with a circumferential groove 16 receiving the upper end 17 of a controller-lever hung upon a stud 18 and having its lower arm 19 engaged with the extension 20 of a governor-lever 21 hung upon a stud 22 and having its lower end formed with a fork 23 entered between collars 24 and 25 upon the projecting outer end of the valve-stem 26 of the balanced steam valve 27 of the motor- 80 controller unit of our improved apparatus, 85 as herein shown.

The said balanced-valve 27 is located within a casing 28 having a steam-inlet 29. A helical-spring 30 surrounding the stem 26 tends normally to open the said valve.

As shown, the apparatus is provided with 90 an emergency-governor unit which may also be of any standard construction. As shown, the said governor has a horizontally ar- 95 ranged spindle 31 engaging at its outer end with the upper end of the lever 21 and 100 having bearing and endwise movement in a nut 32 by which the governor-spring 33 is adjusted as required. At its inner end, the said spindle co-acts with two comple- 105 mentary weights 34 pivotally hung in a cup-like head 35 secured to the projecting end of the main-shaft 36 of the steam turbine 37, which may be of any approved construction and is

connected by a flanged coupling 38 with a centrifugal pump 39, also of any approved construction, and connected by a pipe 40 with the tank 3, the said pipe 40 comprising 5 a T 41 for connection with the service-pipe 42. For convenience of illustration, the tank 3 and service-pipe 42 have been drawn out of scale.

As already explained, our improved apparatus is designed for operation on the principle of a high and a low water-level. When the tank 3 has been filled to its high water-level 6, the pump is automatically stopped by the creation of an amount of water-pressure in the chamber 8 sufficient to act upon the diaphragm 10 to move the operating-head 9 from left to right against the pressure of the spring 13 enough to operate the controller-lever 17, which in turn acts upon 10 the governor-lever 21, which in turn operates the valve 27 of the motor-controller to shut off the steam and hence stop the turbo-pump, the pressure in the chamber 8 being created by the overflow of water rising through the 15 short leg 2 of the siphon, thence passing through the horizontal pipe 5 thereof and downward through the long leg 7 thereof into the water-pressure chamber 8. The tank having been filled to the high water-level 6 and the turbine and pump stopped, 20 the water in the tank is withdrawn therefrom, as required, through the service-pipe 42, and so falls in the tank from its high water-level 6 to its low water-level 5. During 25 this entire period, a small amount of water is constantly being siphoned from the tank into the water-pressure chamber 8 for the maintenance of pressure therein and to replace the water which is constantly dripping 30 therefrom through the cock 15, it being necessary to maintain pressure within the water-pressure chamber 8 during the entire period while the water in the tank is being drawn down from its high level to its low 35 level, since it is the pressure in the chamber 8 which is relied upon to keep the steam-control valve closed, whereby the turbo-pump is kept out of action. When the water in the tank has been drawn down to its 40 low level and therefore below the lower end of the short leg 2 of the siphon, no more water will enter the same from the tank, but

all of the water in the siphon at the time will be passed through the same and through the water-pressure chamber 8 and out of the 55 drip-cock 15. As soon, in this brief interval, as the pressure in the chamber 8 falls below the power exerted by the spring 12, the same will re-assert itself and move and operate the head 9 from right to left, whereby the controller-lever will be operated and act upon the governor-lever 21, which will, in turn, release the spring-actuated balanced-valve 29 so as to re-admit steam to the turbine, which will start the pump which 60 will continue to operate until the tank has been re-filled to its high level, at which time the water flowing through the siphon restores the pressure in the water chamber 8 sufficiently to act upon the operating-head 70 9 to move the same, as required, for shutting off the steam and so stopping the turbine and pump.

It will be seen from the foregoing that the 75 number of times which the apparatus is stopped and started, is reduced to a minimum, as it is only started when the low water-level has been reached in the tank, whereas in ordinary practice, the pump is started in response to slight falls in water-level.

While our apparatus, as described, employs a turbo-pump for filling the tank, it is apparent that an electrically driven pump could be controlled in the same way by substituting a rheostat for the steam-control 80 valve.

We claim:

In an automatic controlling apparatus for tank-pumps, the combination with a tank, 90 of a tank-pump, a motor therefor, a motor-controller, and a hydraulic motor-controller operator including a siphon the high and low points of which substantially coincide with pre-determined high and low water-levels in the tank.

In testimony whereof we have signed this specification in the presence of two subscribing witnesses.

LUCIUS E. WHITON.
HENRY B. LEE.
